UNITED STATES PATENT OFFICE.

CHARLES CONSTANTINE HISCOE, OF NEW YORK, N. Y., ASSIGNOR TO
FREDERICK BECK, OF SAME PLACE.

DESIGN FOR A WALL AND CEILING COVERING.

SPECIFICATION forming part of Design No. 19,599, dated January 21, 1890.

Application filed December 26, 1889. Serial No. 335,038. Term of patent 3½ years.

To all whom it may concern:

Be it known that I, CHARLES CONSTANTINE HISCOE, a citizen of Great Britain, residing at New York, in the county of New York and State of New York, have invented and produced a new and original Design for a Wall and Ceiling Covering, of which the following is a specification, reference being had to the accompanying drawing, forming part thereof.

5 The leading feature of my design consists of vases, figure 1, from which hang floral festoons, figure 2, also ribbon, figure 3. Hanging from handles of vases are bouquets of flowers and leaves, figure 4. There are also plain buttons, figure 5. There is an upper border of

molding and plain blocks, figure 6, and a lower border of beaded half-circles, figure 7, and plain buttons, figure 8.

What I claim is—

The design for a wall and ceiling covering herein shown and described, consisting of vases connected by floral festoons, pendent bouquets, ribbons, plain buttons, and an upper and lower border, the lower border being decorated with beaded half-circles and plain buttons.

CHARLES CONSTANTINE HISCOE.
